UNITED STATES PATENT OFFICE.

DAVID H. WATTS, OF OLDEN, PENNSYLVANIA.

DESIGN FOR A BRUSH-HANDLE.

43,250.

Specification for Design.

Patented Nov. 12, 1912.

Application filed September 11, 1912. Serial No. 719,889. Term of patent 7 years.

To all whom it may concern:

Be it known that I, DAVID H. WATTS, a citizen of the United States, residing in Olden, Delaware county, Pennsylvania, have invented a certain new, original, and ornamental Design for a Brush-Handle, of which the following is a specification, reference being had to the accompanying drawing, forming part thereof.

Figure 1, is a side view, showing the

design; Fig. 2 is a plan view; and Fig. 3, is an inverted plan view.

I claim:

The ornamental design for a brush handle, as shown.

DAVID H. WATTS.
